(57) **CLAIM**

The ornamental design for a sidewall portion of an automobile tire, as shown and described.

DESCRIPTION

The patent or application file contains at least one drawing executed in color. Copies of this patent or patent application publication with color drawing(s) will be provided by the Office upon request and payment of the necessary Fee.

FIG. 1 is a perspective view of sidewall portion of an automobile tire according to a first embodiment of my new design;

FIG. 2 is a front view thereof;

FIG. 3 is a top view thereof;

FIG. 4 is a right side view thereof;

FIG. 5 is a left side of view thereof;

FIG. 6 is a rear view thereof;

FIG. 7 is a bottom view thereof;

FIG. 8 is a fragmentary enlarged view showing the details of the sidewall portion defied by cross-section by lines A-A and B-B in FIG. 2;

FIG. 9 is a section view taken along line 9-9 in FIG. 8;

FIG. 10 is a perspective view of sidewall portion of an automobile tire according to a second embodiment of my new design;

FIG. 11 is a front view thereof;

FIG. 12 is a top view thereof;

FIG. 13 is a right side view thereof;

FIG. 14 is a left side of view thereof;

FIG. 15 is a rear view thereof;

FIG. 16 is a bottom view thereof;

FIG. 17 is a fragmentary enlarged view showing the details of the sidewall portion defied by cross-section by lines A-A and B-B in FIG. 11; and,

FIG. 18 is a section view taken along line 18-18 in FIG. 17. Only the green color (and no other colors) in FIGS. 10-14, 16 and 17 is being claimed.

The broken lines are used to show portions of the tire that are not being claimed, and thus form no part of the claimed design.
